UNITED STATES PATENT OFFICE.

HENRY RUEGG, JR., OF WEEHAWKEN, NEW JERSEY.

HEDDLE.

1,341,245.

Specification of Letters Patent.

Patented May 25, 1920.

Application filed July 16, 1919. Serial No. 311,148.

To all whom it may concern:

Be it known that I, HENRY RUEGG, Jr., a citizen of the United States, and a resident of Weehawken, in the county of Hudson and State of New Jersey, have invented a new and Improved Heddle, of which the following is a full, clear, and exact description.

The invention relates to looms and its object is to provide a new and improved heddle which is simple and durable in construction, cheap to manufacture, and arranged to enable the weaver to thread a warp thread through the eye of the heddle without the use of a hook or similar tool. Another object is to prevent the warp thread from accidentally passing out of the eye on raising or lowering the heddle. Another object is to permit of making the heddle of one single strip of metal or other material.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a face view of the heddle blank;

Fig. 2 is a similar view of the finished heddle;

Fig. 3 is an edge view of the same;

Fig. 4 is a face view of a blank for a modified form of the heddle;

Fig. 5 is a similar view of the modified form of the heddle;

Fig. 6 is an edge view of the same;

Fig. 7 is a face view of a blank for another modified form of the heddle;

Fig. 8 is a similar view of the modified form of the heddle;

Fig. 9 is an edge view of the same;

Fig. 10 is a face view of another modified form of the heddle; and

Fig. 11 is an edge view of the same with a superposed covering strip applied thereto.

The heddle illustrated in Figs. 1, 2, and 3 is formed from a single strip 10 of metal or other material, and the upper portion is made wider than the lower portion and this upper

portion is provided with a split 11 extending from the upper end downward a desired distance to terminate in an approximately almond-shaped opening 12, as plainly indicated in Figs. 1 and 2. The slit 11 forms the upper portion of the strip 10 into two members 13 and 14, of which the member 13 is adapted to be bent over onto the member 14 thus superimposing the members 13 and 14, as plainly indicated in Figs. 2 and 3. The lower ends of the members 13 and 14 are provided with transversely extending bends 15, 16 bent in opposite directions to form an eye 17 for the passage of the warp thread. It will be noticed that the eye 17 is closed by the joint of the lower ends of the members 13 and 14, and the upper end of the eye is closed by the superposed members 13 and 14 and hence the warp thread is not liable to accidentally pass out of the eye on moving the heddle up and down. When it is desired to place a warp thread in position in the eye 17 it is only necessary for the weaver to spread the members 13 and 14 apart, as indicated in dotted lines in Fig. 3, to allow the weaver to readily pass the warp thread between the two members and then slide the warp thread downward until it passes into the eye 17. The members 13 and 14 return by their own resiliency to closed superposed position on being released by the operator. The upper ends of the members 13 and 14 are provided with registering openings 19 through which extends the upper crossbar of the heddle frame, and an opening 18 is formed in the lower end of the strip 10 and through which extends the lower crossbar of the heddle frame.

In the modified form shown in Figs. 4, 5 and 6, the strip 20 is provided in its upper portion with a slit 21 forming two members 22 and 23 having their lower ends 24, 25 bent transversely in opposite directions to form an eye for the passage of the warp thread. The member 22 is provided immediately above the bent portion 24 with a sidewise extending integral lug 26 extending across the slit 21 so as to close the upper end of the eye. The member 22 is bent over and superposed on the member 23 the same as above described in reference to the heddle illustrated in Figs. 1, 2 and 3. The upper and lower ends of the heddle are provided

with openings 27, 28 for engagement by the top and bottom crossbars of the heddle frame.

- 5 In the modified form shown in Figs. 7, 8 and 9, the heddle is formed of a single strip 30 provided in its upper portion with a slit 31 thereby forming the members 32, 33 provided at their lower ends with the bent eye portions 34, 35 for forming the heddle eye, 10 in the same manner as above described in reference to the construction illustrated in Figs. 1, 2 and 3. The two members 32 and 33 in this case are bent toward each other to become superimposed at their upper portions 15 thereby providing a closure for the upper end of the eye. The upper and lower ends of the strip are provided with openings 38, 39 for engagement with the top and bottom crossbars of the heddle frame.
- 20 In the modified form shown in Figs. 10 and 11 the heddle is formed of a single strip 40 provided with an eye formed by two struck-up, vertically disposed lugs 41, 42 arranged in different planes. The lug 41 extends downwardly while the lug 42 extends upwardly and the lugs are spaced apart a sufficient distance for the passage of the warp thread between them to allow the weaver to pass the warp thread first 25 under one lug and then under the other, to thread the warp thread in the eye. The upper and lower ends of the strip 40 are provided with openings 43 and 44 for engagement by the top and bottom crossbars of the 30 heddle frame. In order to prevent the lugs 41 and 42 of one heddle from being caught in the openings formed by the struck-up lugs on an adjacent heddle, use is made of 35 a covering strip 50 having a bent portion 40 51 overlying the lugs 41 and 42. It is understood that the strips 40 and 50 can be readily bent apart to permit of passing the warp thread between the two strips to then engage the warp thread with the lugs 41 45 and 42, as above explained. The upper end of the covering strip 50 is provided with openings 52, 53 in register with the openings 43 and 44 for engagement by the top and bottom crossbars of the heddle frame.

Having thus described my invention, I 50 claim as new and desire to secure by Letters Patent:—

1. A heddle formed of a single strip provided with an eye for the passage of a warp thread, the eye being formed of two eye members 55 integral with the strip and arranged one alongside the other, the eye being normally closed at top and bottom.

2. A heddle comprising a single strip having an eye formed of two eye members 60 bent transversely in opposite directions, the strip being split from the eye to one end to form two members being superposed and closing the eye at the split.

3. A heddle formed of a single strip having a lengthwise extending slit for the passage of a warp thread, and forming two members terminating in eye portions arranged one alongside the other and bent transversely in opposite directions, the 70 members being superposed and forming with the bent portions an eye normally closed at top and bottom, the said slit opening into the eye for the passage of the warp thread into the eye on bending the split 75 members apart.

4. A heddle formed of a single strip provided with a split extending from the top of the strip a distance downward and terminating at its bottom in an enlarged portion, the slit providing two members terminating at their inner ends in eye portions bent transversely in opposite directions and located on opposite sides of the said enlarged bottom end of the slit, the said members 85 being superposed above the said eye portions.

5. A heddle formed of a single strip provided with a slit extending from the top of the strip a distance downward and terminating at its bottom in an enlarged portion, the slit providing two members terminating at their inner ends in eye portions bent transversely in opposite directions and located on opposite sides of the said enlarged bottom end of the slit, and means closing the slit above the bottom portion thereof.

HENRY RUEGG, JR.
